UNITED STATES PATENT OFFICE.

GEDOR W. ALDEEN, OF ROCKFORD, ILLINOIS, ASSIGNOR TO FYRAC MANUFACTURING CO., OF ROCKFORD, ILLINOIS, A CORPORATION OF ILLINOIS.

SPOTLIGHT.

Application filed April 30, 1926. Serial No. 105,625.

The invention hereof relates to adjustable lamps or spot lamps adapted to project beams of light onto any desired spot over a comparatively large field or range and more particularly to that type of lamp well known upon the market as a windshield spotlight which is generally attached to a screen such as the windshield of a motor vehicle or power boat, although the utility of a lamp of this character is of far wider and greater application.

One of the primary objects of my invention is to provide a lamp of the character aforementioned which, with a suitable type of mounting, may be so attached to a screen, such as a windshield, that the lamp proper will lie on one side of the screen and a handle or other means for manipulation thereof will lie on the other side of the screen with the lamp so constructed and arranged in connection with its support that the light beams may be directed at right angles to the screen or at substantially any angle between a right angular direction and a plane parallel with the screen.

A further object of the invention is to provide a lamp mounting of such character as that noted in the foregoing object from which the lamp may be readily removed and, if provided with a cable of sufficient length, may be utilized as a trouble light.

Other objects, including the details of construction and the arrangement of the parts as well as their operation, will or should become apparent from the following description and claims and the drawings in which:

Fig. 1 is a top plan view of one form of a lamp constructed in accordance with the invention mounted in a windshield and showing in dotted and full lines the manner in which the light is operable to obtain a maximum range of light projection.

Fig. 2 is a side elevation of the lamp shown in Fig. 1.

Fig. 3 is a sectional view taken substantially along the line 3—3 of Fig. 2, and

Fig. 4 is a sectional view taken substantially along the line 4—4 of Fig. 3.

Referring more particularly to the drawings I have shown the illustrated embodiment of my invention mounted through an opening 2 provided through a fragment of a windshield 3 and arranged therein for universal movement.

A spot lamp, generally designated 4, is attached to and carried by a ball-like member, generally designated 5, secured in a socket structure for substantially universal movement. This socket structure comprises what may be termed a fix-socket unit, generally designated 6, and a spring socket unit, generally designated 7. The fixed-socket unit includes a socket ring 8 in the form of a cylindrical body peripherally threaded at 9, inwardly flanged at 10 to provide a wall seat 11 and outwardly flanged at the other end, as at 12, to provide an annular clamping flange between which and a clamping ring nut 13, the edges of the windshield or other support adjacent the opening therethrough may be clamped, the ring 13 being provided with threads to engage the threads 9 to thereby draw the ring and flange 12 tightly against the glass. However, to insure a water tight joint between the windshield and the clamping members 12 and 13 suitable washers 14 are interposed between the clamping members and the glass or other support, as may be desired.

The spring socket unit 7 includes a knurled 80 casing 15 provided with a threaded sleeve 16 adapted to engage corresponding threads formed internally on the socket ring 8 and may thereby be removably secured thereto. The spring socket 7 is also provided with an 85 inwardly projecting circumferential flange 17 which serves to retain a circular coiled spring 19 which normally urges a frusto-conical ring 20 providing a seat 21 for the ball-like member 5 opposed to seat 11, against the ball-like 90 member 5 under sufficient pressure to frictionally hold the ball with the lamp and other parts in adjusted position. Tension of spring 19 against the ring 20 and thus the friction imposed on the ball-like member 5, may be adjusted by unscrewing or screwing up on the spring socket housing 8. A ring 21, which I shall hereafter term a positioning or an abutment ring, is of inside diameter slightly greater than the outside diameter of the ball-like member 5 and preferably is of such thickness that its outside diameter will be substantially the inside diameter of the sleeve portion 16 of the spring socket or spring container unit 7, while the width of the abutment ring is preferably sufficient to position its forward edge 22 in a diametral plane through the ball-like member 5 when its rear edge 23

is abutting against the inturned seat flange 10 of the socket ring 8. The purpose of the abutment ring 21 will be later described.

The ball-like member 5 is preferably formed of two substantially symmetrical hemispheres 24 and 25, each of which is recessed as at 26 and 27 for the reception of a cylindrical stem 28 upon which the lamp 4 is supported at one side of the windshield or other wall 3 and upon which an operating handle generally designated 29 is supported at the opposite side of the wall or windshield. The stem 28 is bifurcated from some point 30 slightly to the rear of the ball-like member 5 through the ball and to some suitable point forward thereof where the two halves are bent outwardly to provide a yoke-like support, the opposite arms of which are indicated at 31 and 32. The arms 31 and 32 are preferably rolled or flanged at their sides, as indicated at 33 and 34, to strengthen and to increase the artistic appearance of the product, while at their outer ends they are provided with aligned openings through which one or more hollow and aligned pivot pins 35 are passed and upon these pivot pins the lamp is pivotally supported, as will more clearly appear.

The lamp itself is preferably composed of inner and outer shells 36 and 37, the inner shell serving both as a reflector and a support and socket for the lamp bulb 38 and the outer shell serving as a protecting casing or cover for the inner shell and as a lamp manipulating element, as will more particularly hereinafter appear. A lens 39 is suitably secured between a clamping ring 40 and the reflector shell 36 in any suitable manner while an annular outwardly projecting bead 41 on the clamping ring provides an internal recess within which a spring snap ring 42 is positioned to secure the inner shell 36 in position. The clamping ring 40 is provided with bayonet slots or other suitable openings through which screws 43 pass in order to secure it to a flange 44 formed integral with the outer shell of casing 37. Behind the flanged portion 44 the outer shell or casing 37 is provided with connections in the form of projections 45 for pivotal engagement with the pivot pins 35. At least one of the pivot pins 35, as aforesaid, is made hollow for the passage of an electrical conducting wire or wires 46 and threaded externally at one end for the reception of a nut 47 which is secured in position by a lock washer 48, while its opposite end is provided with a head to abut against the outer side of the arms 31 and 32. Suitable washers 49 and 50 may be interposed between the arms 31 and 32 and the pivot connection portions of the casing 37, but if this be done, an opening must be provided through one of them for the passage of electrical conductors 46 which, as will be noted, pass through the stem and the center of the ball-

like member 5 into the handle 29 where they are connected through a switch mechanism, the operating handle of which is indicated at 51, to a cable 52 leading to a suitable source of electric current supply.

With the spotlight so described it will be appreciated that the handle 29 may be manipulated to direct the light beam in any direction within the limits of contact of the stem 28 with the housing or universal socket structure, assuming of course, that the lamp proper remains in fixed position with respect to the stem. Owing to the fact that abutment of the stem against the socket or universal member housing structure limits direction of the light beam beyond, say a thirty degree angle with respect to the plane of the wall or windshield through which the lamp is mounted, it is impossible without changing the position of the vehicle or wall in which the lamp is mounted to illuminate objects substantially on the line with the wall or windshield. This is a serious handicap in many instances, but through a unique arrangement which will now be described I have overcome this deficiency of spotlights of this character so that the light beam may be directed substantially along or even behind a line or plane parallel with the wall or windshield through which the lamp is mounted.

The lamp shell 37 is provided with an arcuate rack 53 (in this instance shown as integral with the shell) which meshes with a sector gear 54 formed integral with a ring 55 seated in recesses provided in each hemisphere 24 and 25 of the ball-like member 5. The rack 53 is aligned with the sector gear 54, which in turn is positioned in the recess formed by the bifurcation of the stem 28. The ring-like portion 55 is provided with outwardly projecting shoulders 56 for abutting but sliding engagement with the outer edge of the abutment or position ring 21. In this manner the sector gear 54 is held against rotation in either direction about the axial center of the ring portion 55, but as it is retained between the upper and nether hemispheres 24 and 25 which are secured together by means of a counter-sunk screw 57, rotation of the ball-like member 5 about the major axis of the stem 28 will also rotate the sector gear with the lamp proper about the same axis. An insulating bushing 58 is preferably positioned about the screw 57 where the conducting cord 46 passes in order to prevent abrasion of the insulating coating of the conductor by the threads of the screw.

In operation, viewing Figs. 1 and 3, the handle 29 is grasped and may be moved in the plane of the paper in either direction from its full line position shown. Since the sector gear in this case is held stationary relatively to the housing and wall and the ball-like universal member 5 swings correspondingly with movement of the stem and the

lamp, trunnions or pivots 35 are swung in arcuate paths toward the wall. The rack 53 engaging with the sector gear 54 is moved to swing the lamp on its pivots or trunnions 5 until at the limit of the movement of the handle the lamp has reached a position, such as that illustrated in dotted lines in Fig. 1, where the light beam will be projected in a path substantially parallel to the line of the wall. 10 It will be apparent, of course, that depending on the lengths of the sector gear and rack the light beams may be projected toward the wall or windshield 3.

The operation, as above described, provides 15 for manipulation of the lamp to the greatest possible range in one projection plane which might in some instances be sufficient, but since there is sliding engagement between the shoulders 56 of the ring 55 and the outer edge of 20 the positioning or abutment ring 21, rotation of the handle 29 about the major axis of the lamp and stem rotates the sector gear so that this plane of greatest light beam sweep or 25 projection may be turned at any angle about the major axis of the stem and lamp and a maximum beam sweep obtained in any plane perpendicular to the plane of the wall, windshield or other screen.

It will be apparent, of course, that means 30 other than a gear and rack may be utilized for manipulation of the lamp proper about its pivot and that the axis of the lamp may be disposed at an angle to the axis of the stem other than a straight angle and the sector 35 gear and ring or the sector gear alone disposed other than perpendicular to the plane of the wall, windshield or other screen through the lamp is mounted.

The spotlight is arranged to be secured on 40 the inside against unauthorized removal from without. The interior clamping ring nut or clamping member 13, is provided with a small lug or projection 60, preferably integral therewith, which is drilled and tapped for the 45 reception of a set screw or stud 61 adapted to bear against a horizontal portion of the member 13 and press or spring the same tightly into engagement with the threaded portion 9 of the socket ring 8 and frictionally lock it 50 thereto. In order that the horizontal portion of the member 13 may yield sufficiently for this purpose it may be recessed, or preferably cut through, as shown at 62 in Figs. 1, 2 and 4, although other expedients may be 55 resorted to and the portion between the ends of the kerf 62 may be thinned in order that it may be depressed slightly by action of the locking set screw.

As such modifications obviously fall within 60 the spirit and scope of my invention and as many other modifications and changes in construction and operation may readily be conceived as within the field of my invention, I do not desire to be limited to the details 65 of construction and arrangement utilized sole-

ly for the purpose of illustrating what is at present a preferred embodiment but only by the purview of the appended claims.

I claim:

1. In a spotlight, a housing adapted to be 70 mounted in a wall, a support movably mounted in said housing and projecting therefrom in opposite directions beyond said wall, a lamp carried by said support at one side of said wall, a handle rigidly and non-rotatably secured to the other end of said support whereby said support and lamp may be moved as a unit relatively to the housing, and means operative upon swinging movements 75 of said handle to move said lamp with respect to said support.

2. In a spotlight, a housing adapted to be secured in relatively fixed position, a lamp support mounted in said housing for substantially universal movement with respect 85 thereto, a lamp connected to said support and movable therewith and with respect thereto, a light manipulating member connected to said support for moving said support substantially universally, and means operated by 90 predetermined swinging movements of said member for moving said lamp with respect to said support.

3. In a spotlight, a housing adapted to be 95 mounted in a wall, a support movably mounted in said housing and projecting therefrom in opposite directions beyond said wall, a lamp carried by said support at one side of said wall, a handle rigidly and rotatably secured to the other end of said support whereby 100 said support and lamp may be moved as a unit relatively to the housing, and means including gearing operative upon swinging movements of said handle to move said lamp with respect to said support.

4. In a spotlight, a housing adapted to be secured in relatively fixed position, a lamp support mounted in said housing for substantially universal movement with respect 110 thereto, a lamp connected to said support and movable therewith and with respect thereto, a light manipulating member connected to said support for moving said support substantially universally, and means including 115 a gear operated by predetermined swinging movements of said member for moving said lamp with respect to said support.

5. In a spotlight, a housing having an opening at one side thereof, a member mounted for substantially universal movement in said housing, a stem connected to and projecting from said member and through the opening on one side of said housing, a spotlight pivotally connected to said stem, means connected with said member for rotational movement with said member about the axis of said housing and secured against pivotal movement relative to said spotlight, means connecting said lamp and first said means whereby said lamp and 130

first said means may be moved relatively and together, and a single handle non-rotatably secured to said member for moving said member.

- 5 6. In a spotlight, a ring housing having openings at opposite sides thereof, a universally movable member mounted within said housing and having stems connected on opposite sides thereof, projecting therefrom 10 and through said openings in the housing, a spotlight secured to one of said stems for swinging movement in one plane relatively thereto, and means connected to said spotlight, housing and member whereby rotational movement of the other stem about its axis and swinging movement about an axis of said member parallel the axis of said spotlight pivot will correspondingly rotate and swing said spotlight, respectively.
- 15 7. In a spotlight, a ring housing having aligned openings at opposite sides thereof, a stem, a spotlight pivoted to said stem, a member mounted within said housing for substantially universal movement with respect thereto and connected to said stem through 20 one of said openings whereby rotation of said member about certain axes will rotate said stem and spotlight, means projecting from said member and movable therewith only 25 about one axis of said member, means for connecting said projecting means and spotlight whereby movement of said member about one axis will swing said spotlight about its pivot, and means projecting through the opening in 30 the housing opposite said stem for moving said member universally.

- 35 8. A wall receivable spotlight comprising, a housing adapted to be secured in a wall and having openings on opposite sides of the wall, 40 a universally movable member within said housing, a stem secured to said member and projecting through one of said openings in said housing to one side of the wall, a spotlight pivoted to said stem at a point spaced 45 from said housing, a device secured within said housing and connected to said member for movement therewith about all but one of the axes of the member about which the member is moved, said member and device being 50 relatively movable about said one axis with respect to said wall, means connecting said device and spotlight whereby movement of said member about the axis of relative movement of said member and said device will 55 swing said spotlight about its pivot and movement of the member about another of its axes will rotate said spotlight and device together, and means for moving said member about a plurality of axes including the axes 60 mentioned.

- 65 9. A spotlight of the class described comprising, a lamp, a pivot support for said lamp, a housing adapted to be secured to and through a wall, a universal mounting in said

housing and connected to said support, a device connected to said universal mounting to move therewith upon certain movements thereof, said device and mounting being relatively movable upon certain other movements of the mounting, means connecting said device and lamp whereby movement of said mounting relatively to said device will swing said lamp about its pivot, and a single handle rigidly and non-rotatably secured to said mounting for moving said universal mounting universally.

70 10. In a spotlight, a housing having an opening at one side thereof, a member mounted for substantially universal movement in said housing, a stem connected to and projecting from said member and through the opening on one side of said housing and bifurcated at its end remote from said housing, a spotlight trunnioned between the bifurcated portions of said stem, means connected with 80 said member for rotational movement with said member about the axis of said housing and secured against movement about an axis perpendicular to the axis of said housing, means connecting said lamp and first said 85 means whereby said lamp and first said means may be moved relatively and together, and manually operable means for moving said member.

90 11. In a spotlight of the class described comprising, a bifurcated support, a lamp pivotally trunnioned between the bifurcated portions of said support, a housing adapted to be secured to and through a wall, a universal mounting in said housing and connected to said support, a device connected to said universal mounting to move therewith upon certain movements thereof, said device and mounting being relatively movable upon certain other movements of the mounting, 100 means connecting said device and lamp whereby movement of said mounting relatively to said device will swing said lamp about its pivot, and means for moving said universal mounting universally.

110 12. A spotlight of the class described comprising, a lamp having an inner shell providing a reflector and an outer substantially concentric shell providing pivot connections, a support pivotally connected to said pivot 115 connections, a housing adapted to be secured to and through a wall, a universal mounting in said housing and connected to said support, a device connected to said universal mounting to move therewith upon certain movements thereof, said device and mounting being relatively movable upon certain other movements of the mounting, means connecting said device and outer shell whereby movement of said mounting relatively to said device will swing said lamp upon said pivots, 120 and means for moving said universal mounting universally.

13. A spotlight of the class described comprising, a lamp including a casing, a support for said lamp pivotally connected to said casing, a housing adapted to be secured to and through a wall, a universal mounting in said housing and connected to said support, a device having outwardly directed gear teeth and connected to said universal mounting to move therewith upon certain movements thereof, said device and mounting being relatively movable upon certain other movements of the mounting, a gear on the rear of said casing and engaging said teeth on said device and connecting said device and lamp casing whereby movement of said mounting relatively to said device will swing said lamp about its pivot, and a handle non-rotatably

connected to said mounting for moving said universal mounting universally.

14. As an article of manufacture, a lamp casing of generally parabolic cross section provided with a rack integral therewith on the convex side thereof.

15. In a windshield spotlight, a pair of co-operative glass clamping members, a portion of one of said members being adapted to yield toward the other in a plane substantially parallel the plane of the windshield, and means for urging said portion toward the said other member for securing said members together.

In witness of the foregoing I affix my signature.

GEDOR W. ALDEEN.
